UNITED STATES PATENT OFFICE

2,446,210

AIRPLANE DEICING AND ENGINE
SILENCING CONSTRUCTION

Fred P. Chadsey, Fillmore, Calif.

Original application October 2, 1942, Serial No. 460,547, now Patent No. 2,396,684, dated March 19, 1946. Divided and this application December 29, 1945, Serial No. 638,252

1 Claim. (Cl. 244—134)

1

This is a divisional application of my copending application Serial No. 460,547, now Patent No. 2,396,684, dated March 19, 1946.

The present invention relates to new and useful improvements in airplanes and more particularly to means for de-icing the wings, body or fuselage, rear elevators and rudder.

An important object of the invention is to provide connections for the exhaust manifold of the engines of the airplane to distribute the exhaust gases over the desired parts and thus supply sufficient heat to prevent formation of ice thereon.

Another object is to provide an improved airplane construction which adds to the efficiency and control of the machine and thus improve the safety thereof and which is also inexpensive to manufacture and otherwise well adapted for the purpose for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a plan view of the invention.

Figure 2 is a front elevational view thereof.

Figure 3 is a fragmentary side elevational view.

Figure 4 is a transverse sectional view of the wing construction, and

Figure 5 is a horizontal longitudinal sectional view thereof.

Referring now to the drawings in detail the numeral 5 designates the body or fuselage of the airplane having wings 6, rudder 7 and rear elevators 8. In advance of the rudder is the upstanding fin 9.

The body or fuselage is formed of inner and outer spaced shells 16 and 17 to form an insulated air space 18 therebetween, the front end of the air space being closed by a transverse partition 19.

Projecting above the body adjacent the wings are a plurality of air discharge nozzles 23 connected to the air space 18, the nozzles being of flat flaring form disposed horizontally and directing the heated air from the nozzles fanwise over the upper surface of the body.

Nozzles 24 and 25 project outwardly from opposite sides of the body adjacent its rear end and also communicate with the air space 18, the nozzles 24 and 25 likewise being of flat flaring form and are disposed horizontally immediately in advance of the elevators 8.

Projecting upwardly from the top of the body at its rear end immediately in advance of the fin

2

9 is a nozzle 26 communicating with the air space 18 and also of flat flaring form and vertically disposed to thread the heated air over the fin.

The wings have motor nacelles 29 mounted in the leading edges thereof, it being understood that any desired number of motors may be provided.

Annular exhaust manifolds 30 surround the motors from which exhaust pipes 31 extend, the exhaust pipes 31 extending rearwardly to a flat elongated manifold 33 extending along the leading edge of the wings.

A sectional defroster conduit designated generally at 34 is conformably fitted on top of the wing 6 substantially coextensive therewith and is composed of a substantially flat box-like front section 35 and rear section 36 secured to the wing by straps 37 and bolts 37a threaded in angle brackets 37b at the front and rear edges of the wings. One edge of each section is in abutting relation and the abutting edges of the outer ends of the sections are open to provide communication with each other.

The manifold 33 is secured on top of the front section and communicates therewith by means of a passage 38 at the inner end of the front section, while the rear section at its inner end communicates with the air passage 18 of the body or fuselage by a pipe 39.

Stay bolts 40 brace the top and bottom surfaces of the sections of the defroster.

From the foregoing it will be apparent that the exhaust gases from the engine will pass through the manifold 30 into the front section 35 of the defroster and will then travel toward the outer end thereof as indicated by the arrows in Figure 5 into the rear section 36 and thence into the air passage 18 of the fuselage for subsequent discharge through the nozzles.

The distribution and dissipation of the exhaust gases as indicated further reduces the noise of the motors to produce a quieter running airplane.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein

described and the scope of the appended claim.
What is claimed is:

An airplane wing de-icing construction comprising a sectional flat hollow member, means detachably connecting the sections to the top of the wing with one section of the member arranged in advance of the other, said sections having communication adjacent the outer end of the wing, and a manifold supported on top of the member and connected to a power plant employed for driving the airplane, said manifold being connected to the front section and extending along the front edge thereof with one end communicat-

ing therewith at the inner end of the wing and the rear section having a discharge port at the inner end of the wing.

FRED P. CHADSEY.
